DOFF SAFETY BRACKET FOR LOOMS

Arthur L. Thibault, Fall River, Mass.

Application February 1, 1952, Serial No. 269,368

2 Claims. (Cl. 139—193)

1

This invention comprises novel and useful improvements in a doff safety bracket for looms and more specifically pertains to an attachment for looms for positively preventing smashing by positively preventing the contact of a bobbin which may be upended in its seat in a shuttle at the beginning of the picking operation of the shuttle, from contacting the warp threads of the shed of a loom.

The primary object of this invention is to provide an attachment which will positively engage and obstruct further movement of an upended bobbin of a shuttle during the picked flight of the latter across the lay of a loom thereby preventing the possibility of an upended bobbin from engaging the warp threads of the loom shed during the passage of the shuttle across the lay of the loom.

A further object of the invention is to provide an attachment which will be of simple, inexpensive and lightweight construction, and may be readily applied to existing conventional structures of reed caps and lays of conventional looms.

A still further object of the invention is to provide an attachment in conformity with the foregoing object which may be mounted upon the reed cap of a loom in an improved manner and will stop further operation of a loom if a bobbin becomes upended in its shuttle.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a top plan view of a portion of a loom reed assembly with the present invention applied thereto;

Figure 2 is a front elevational view of the construction of Figure 1;

Figure 3 is a vertical transverse sectional view through a portion of a loom reed structure showing the present invention applied thereto;

Figure 4 is a perspective view of one of the pair of brackets forming the attachment of the present invention; and

Figure 5 is a fragmentary view similar to Figure 2 but showing the manner in which the device functions to engage an upended or displaced bobbin in its seat in the shuttle.

Referring now more specifically to the accompanying drawings, wherein like numerals designate similar parts throughout the various views, it will be seen that there has been illustrated a

portion of a conventional form of loom, which, for example, may comprise the well known Draper loom, and which reed structure includes the reed cap 10 together with the lay 12 carried by the lay swords 14, the lay having associated therewith the usual shuttle boxes 16 and 18 disposed upon the battery and handle ends of the loom. In addition, there is disclosed a portion of the picker sticks 20 and a shuttle 22 is likewise illustrated having a conventional bobbin or spool 24 therein. It is with these conventional loom elements that the present invention is specifically adapted to be utilized.

As is well known, if the bobbin 24 becomes upended or dislodged from its proper position within the shuttle 22, as by being upended as indicated in Figure 5 at the beginning of the picking motion of the shuttle by the picker sticks, the upended portion of the bobbin is liable to catch upon the warp threads of the shed of the loom. When this occurs, the threads are damaged and the operation of the loom must be stopped to repair this damage which is known as smashing.

In accordance with the present invention, a pair of brackets are applied to the reed portion of the loom in such a position as to positively engage and halt further progress of a bobbin upended from its seated position within a shuttle; but will not interfere with passage of the shuttle or bobbin if the latter is properly seated, during the beginning of the picking operation.

The brackets forming the essential elements of this invention may be of identical construction, and each consists of an elongated flat strip of material such as metal or the like. The brackets, indicated generally by the numeral 26, are mounted upon the reed adjacent the shuttle boxes as shown in Figure 2. Each bracket comprises a relatively short upper end portion 28 provided with a pair of securing apertures 30 together with a considerably longer lower end portion 32 which is displaced from but disposed parallel with the upper portion 28. The lower portion is welded or otherwise secured to the mid-portion 34 of a U-shaped clip 36 having apertured mounting flanges 38.

The upper end portion 28 and the clip 36 attached to the lower end portion 32 are adapted to be secured as by screws or the like, as shown in Figure 3, to the sides of the reed cap and lay 16 and 12, respectively.

The bracket further includes an intermediate portion which is reversely curved, consisting of an upper horizontally extending portion 40 adapted to underlie the lower surface of the reed

cap 10 and a downwardly and outwardly curving lower portion 42 which extends downwardly and outwardly with respect to the reed cap and overlies the lay. It is this lower portion 42 which constitutes the actual guard member of the attachment, and this lower portion is preferably disposed above the lay a sufficient distance to permit free passage of the shuttle when the bobbin is properly seated therein, as in Figure 2, but when a bobbin is upended from its properly seated position in the shuttle, whereby passage of the shuttle with the misplaced bobbin therein would cause smashing of the shed by the upended bobbin, the bracket portion 42 will strike the under side of the upended bobbin. This will further raise the bobbin resulting in either stopping the flight of the shuttle or stripping the bobbin therefrom. In either event, smashing of the shed threads will be positively prevented.

The engagement of the bobbin by the bracket portion 42 will result in automatically stopping the loom, whereby the defect must be corrected before the operation may be resumed.

It will be understood that the dimensions of the attachment bracket 26 are such as to enable the same to be appropriately placed upon the reed cap and lay of a loom.

From the foregoing the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having thus described the invention, what is claimed as new is:

1. A smash preventer for loom reeds comprising in combination with a reed cap and lay a pair of brackets disposed adjacent the battery and handle end of a loom, each bracket comprising an elongated flat strip, means securing the ends of said strip to the reed cap and lay, the strip having an intermediate reversely curved portion disposed between the reed cap and lay and positioned above the lay a sufficient distance to clear a shuttle when picked but to engage a bobbin when it is upended in the shuttle wherein said ends of said strip are secured by said securing means to the lateral face of the reed cap and lay.
- 10 2. A smash preventer for loom reeds comprising in combination with a reed cap and lay a pair of brackets disposed adjacent the battery and handle end of a loom, each bracket comprising an elongated flat strip, means securing the ends of said strip to the reed cap and lay, the strip having an intermediate reversely curved portion disposed between the reed cap and lay and positioned above the lay a sufficient distance to clear a shuttle when picked but to engage a bobbin when it is upended in the shuttle, said securing means to the lateral face of the reed cap and lay.
- 15 3. A smash preventer for loom reeds comprising in combination with a reed cap and lay a pair of brackets disposed adjacent the battery and handle end of a loom, each bracket comprising an elongated flat strip, means securing the ends of said strip to the reed cap and lay, the strip having an intermediate reversely curved portion disposed between the reed cap and lay and positioned above the lay a sufficient distance to clear a shuttle when picked but to engage a bobbin when it is upended in the shuttle, said intermediate portion having a part sloping downwardly and outwardly from the reed cap.
- 20 4. A smash preventer for loom reeds comprising in combination with a reed cap and lay a pair of brackets disposed adjacent the battery and handle end of a loom, each bracket comprising an elongated flat strip, means securing the ends of said strip to the reed cap and lay, the strip having an intermediate reversely curved portion disposed between the reed cap and lay and positioned above the lay a sufficient distance to clear a shuttle when picked but to engage a bobbin when it is upended in the shuttle, said intermediate portion having a part sloping downwardly and outwardly from the reed cap.
